UNITED STATES PATENT OFFICE.

CHARLES RODIN, OF CAMBRIDGE, MINNESOTA.

STUMP-PULLER.

1,168,559.

Specification of Letters Patent.

Patented Jan. 18, 1916.

Application filed June 16, 1915. Serial No. 34,449.

To all whom it may concern:

Be it known that I, CHARLES RODIN, a citizen of the United States, residing at Cambridge, in the county of Isanti and State of Minnesota, have invented certain new and useful Improvements in Stump-Pullers; and I do hereby declare the following to be a full, clear, and exact description of the invention, such as will enable others skilled in the art to which it appertains to make and use the same.

This invention relates to devices for pulling tree stumps out of the ground; and it consists in the novel construction and combination of the parts hereinafter fully described and claimed.

In the drawings, Figure 1 is a side view of stump pulling devices constructed according to this invention, and showing the clamp gripping the rope. Fig. 2 is a side view of the clamp, showing the jaws open. Fig. 3 is an end view of the clamp.

These devices are used by connecting them to two tree stumps 2 and 3 which are conveniently near together, and they are constructed so that much loss of time in adjusting the length of the pulling rope or cable 4 is saved. The pulling rope or cable 4 is attached at one end to the stump 2, and its other end portion is wound upon any suitable drum or winding mechanism which is operated in any approved manner. A cord 6 is fastened around the other tree stump 3, and has a ring 7 at its free end. A slideable clamp is provided for connecting the ring 7 to the pulling rope or cable 4. This clamp is formed of two parallel clamping jaws 8 and 9 having their adjacent edges 9 grooved so as to engage with the rope. Levers 12 are provided and are arranged in a series parallel to each other and crosswise of the clamping jaws. These levers are pivoted to the jaw 8 by pins 14, and to the jaw

9 by pins 15. Bars 16 are pivoted to the projecting free end portions of the levers 45 12 by pins 17, and these bars have a loop 18 at one end which engages with the ring 7.

The pulling drum or other winding mechanism is secured to any convenient anchor stump which is strong enough and which is 50 not shown. The cord 6 and the pulling rope 4 are fastened around any two stumps which are conveniently located and which are not too large for the anchor stump. The clamp or take up is placed upon the pulling rope 55 4 by hand, the jaws being slid along the rope 4, or the rope 4 being slid through the jaws, as found convenient and until the parts assume the positions shown in Fig. 1 and the cord 6 is taut and the jaws are in 60 frictional engagement with the rope 4. The portion of the rope 4 between the clamp or take up and the stump 2 need not be taut, and it is usually not in line with the portion of the rope 4 between the clamp and the 65 pulling drum. The clamp is clamped on the rope 4 anywhere convenient so as to pull two selected stumps.

By the use of this device two stumps can be pulled at each pulling operation of the 70 drum, and much time, usually wasted in pulling in slack pulling rope, is saved.

What I claim is:

In stump pulling devices, a pulling cable for attachment to a stump, a ring provided 75 with means for securing it to a second stump, and a clamp comprising two parallel jaws for engaging the pulling cable, a series of levers pivoted to the jaws and arranged crosswise of them, and a bar pivoted to the 80 projecting free end portions of the levers and having a loop at one end which engages with the said ring.

In testimony whereof I have affixed my signature.

CHARLES RODIN.
